 corporation of Ohio

Application May 3, 1950, Serial No. 159,702

11 Claims. (Cl. 277—20)

1

The invention relates generally to faucets for dispensing carbonated beverages, and more particularly to a faucet of novel design and construction for dispensing selectively high or low pressure carbonated water, and syrup alone or simultaneously to be mixed with the carbonated water.

A conventional type of faucet for dispensing carbonated water and flavoring syrup separately from a spout for being mixed in a glass, is shown in U. S. Patent No. 2,401,914 issued June 11, 1946, to C. V. Di Pietro. This type of faucet comprises a cylindrical shutter valve rotatable in a cast body and having U-shaped ports for connecting inlet and outlet passageways in the body, and a gasket is required for making a tight seal between the flat slidably abutting surfaces of the shutter valve and the faucet body, which gasket is subject to constant wear. Due to the sticky nature of the syrup, it tends to build up a residue around the port openings on the surface of the shutter, and collect lint and foreign matter at those points.

With this conventional type of faucet, substantial time and expense are required in drilling the U-shaped ports in the shutter and the passageways in the body accurately, and moreover, difficulty is had in making a tight connection between the inlet passageways in the body and the supply tubes conducting the syrup and carbonated water to the body. These connections require brazing or soldering, which is a troublesome operation because the supply tubes are required to be of corrosion-resistant material such as stainless steel.

Another disadvantage with this conventional type of faucet is that the faucet body is connected, as by brazing, to the faucet arm to give a tight joint, and a straight arm is therefore not interchangeable with a gooseneck arm after the faucet is completed.

Still another and very serious disadvantage with this conventional type of faucet is that the passageways in the shutter and the body are very difficult to clean because of their crooked nature including several angular bends, and this is particularly true of the syrup passageways because of the sticky residue which collects therein, especially at the bends.

It is an object of the present invention to provide a novel beverage dispensing faucet which does not require a shutter valve or any large flat slidably abutting surfaces between the valve and valve body causing excessive wear and also building up of the syrup residue and foreign matter around the ports.

Another object is to provide a novel beverage dispensing faucet in which the inlet passageways extend straight through the faucet and are accessible from the front end thereof so that they

2

can be easily cleaned at any time with a brush.

Another object is to provide a novel beverage dispensing faucet having straight through inlet passageways and valve seats in said passageways, so that the valve seats can be cleaned simultaneously with the passageways.

A further object is to provide a novel beverage dispensing faucet which has a detachable sealing joint at its rear end with the faucet arm, so that it can be used interchangeably with a straight arm or a gooseneck arm, and easily disconnected at the joint for thorough cleaning.

Another object is to provide a novel beverage dispensing faucet which is made entirely from stainless steel bar stock, and requires no castings, and in which the ends of the supply tubes are connected to the faucet arm and do not require separate connection with the faucet body.

A still further object is to provide a novel beverage dispensing faucet which is substantially self-flushing and self-cleaning because the liquids flow through only one angular bend, and because the valves open axially away from the valve seats so as to flush out any foreign material tending to accumulate at those points.

These and other objects are accomplished by the parts, improvements, combinations and arrangements comprising the present invention, a preferred embodiment of which is shown in the accompanying drawings as exemplifying the best known mode of carrying out the invention, the invention being described in detail in the accompanying specification, and the scope of the invention being set forth in the appended claims forming part hereof.

In general terms, the novel faucet comprising the present invention may be described as having a preferably cylindrical body with a plurality of passageways extending longitudinally therethrough and having means for making a detachable sealing joint between the rear end of the passageways and the front end of the faucet arm, there being a removable cap on the front end normally covering the front ends of said passageways and compressing springs in the passageways which hold valves seated on valve seats therein, there being release pins engaging shoulders on certain of the valves and a handle having cam means for actuating said release pins to open said valves against spring pressure, and there being a push lever in front of the cap for opening one of the valves against spring pressure.

Referring to the drawings forming part hereof, in which a preferred embodiment of the invention is shown by way of example:

Figure 1 is a side elevation of the improved faucet connected to a faucet arm, showing various positions of the handles in dotted lines; Fig. 2 is a front end elevation thereof;

Fig. 3 is a fragmentary longitudinal section thereof;

Fig. 4 is a fragmentary transverse sectional view as on line 4—4, Fig. 3;

Fig. 5 is a fragmentary rear end elevation of the faucet body with the gasket removed;

Fig. 6 is a transverse elevation as on line 6—6, Fig. 3;

Fig. 7 is a fragmentary plan section as on line 7—7, Fig. 6;

Fig. 8 is a fragmentary longitudinal sectional view, partly in elevation, as on line 8—8, Fig. 4;

Fig. 9 is a fragmentary longitudinal sectional view as on line 9—9, Fig. 4;

Fig. 10 is a fragmentary longitudinal sectional view as on line 10—10, Fig. 4; and

Fig. 11 is a fragmentary plan sectional view as on line 11—11, Fig. 4.

Similar numerals refer to similar parts throughout the several views of the drawings.

The novel beverage dispensing faucet of the present invention has a preferably cylindrical body 12, which may conveniently be made from stainless steel bar stock, so that all passageways therein will have corrosion-resistant surfaces not affected by liquids flowing therethrough such as carbonated water and flavoring syrups. The rear end of the body 12 is adapted for detachable connection with the shank of a faucet arm, and a straight faucet arm 13 is shown connected to the faucet body 12 in Figs. 1 and 3, but it will be understood that a gooseneck faucet arm may be connected in the same manner within the scope of the invention.

As shown in Fig. 1, the rear end of the arm 13 is provided with a shoulder abutment 14 for abutting a supporting wall or the like, and a hollow threaded tube 15 extends rearwardly from the abutment 14 and has a clamping nut 16 screwed thereon. Flexible metal supply tubes 17 and 18 of corrosion-resistant material are located within the faucet arm for conducting the carbonated water and syrup to the faucet, and these tubes are secured as by brazing in the shank 19 of the arm and terminate in the flat front surface 20 of the shank in register with inlet passageways extending through the faucet body.

The rear end of the faucet body 12 is provided with a circular recess 21 surrounded by a flat annular surface 22 for abutting the flat surface 20 of the shank, and a disk washer 23 of resilient material is fitted into the recess 21 for abutting the surface 20 to make a tight joint or seal around the registering tubes and passageways. Preferably, the end of the shank 19 is provided with an annular shoulder 24 which is engaged by an interior shoulder on a nut 25 screwed onto the reduced rear end 26 of the body, so that the flat surfaces 20 and 22 can be drawn tightly together and compress the gasket to make a tight leak-proof joint. Preferably, a dowel pin 27 extends through the joint into the shank 19 and body 12, for maintaining the ports and passageways in proper registry.

Referring to Fig. 5, the rear end of the inlet passageway for the carbonated water is indicated at 28 and this passageway is located so as to be in register with the carbonated water supply duct 17 in the shank. The rear end of the syrup passageway is shown at 29, and this passageway is located so as to be in register with the end of the syrup supply duct 18 in the shank. The disk washer 23 is provided with ports 28' and 29' registering with the ports or tubes in

the shank and the ends of the passageways 28 and 29 in the body, as shown in Figs. 9 and 10.

Referring to Fig. 10, the carbonated water inlet passageway 28 extends longitudinally toward the front of the body 12, and communicates axially with an enlarged valve bore or passageway 30, the shoulder 31 formed between the passageways 28 and 30 being a valve seat for the cylindrical valve 32 slidably mounted in the enlarged passageway 30. The front end of the passageway 30 communicates axially with a further enlarged bore 33 which allows longitudinal movement of an annular flange 34 secured on the front end of the valve 32. Preferably, an O-ring packing 35 is provided in a groove around the valve 32 positioned adjacent to its inner end, for sealing off fluid entering the bore 30 when the valve is open. The rear end of the valve 32 may be provided with a disk insert 36 of resilient material for making a tight seal with the seat 31 when the valve is closed. A passageway or duct 37 communicates at its upper end with the bore 30 in front of the valve seat 31, and the duct 37 extends downwardly at right angles for discharging into a spout 38 screwed into the under portion of the body 12, as best shown in Fig. 6.

Referring to Fig. 9, the syrup inlet passageway 29 extends longitudinally toward the front of the body 12 and communicates axially with an enlarged bore or passageway 30', the shoulder 31' formed between the passageways 29 and 30' being a valve seat for a cylindrical valve 32' slidably mounted in the bore 30'. The front end of the bore 30' communicates axially with a further enlarged bore 33' which allows longitudinal movement of an annular flange 34' secured on the front end of the valve 32'. Preferably, an O-ring packing 35' is provided in a groove around the valve 32' adjacent to its inner end for sealing off fluid entering the bore 30' when the valve is open. The rear end of the valve 32' is preferably provided with a disk insert 36' of resilient material for making a tight seal with the valve seat 31' when the valve is closed.

As shown in Figs. 6 and 9, a discharge passageway or duct 39 communicates at its upper end with the bore 30' in front of the valve seat 31', and the duct 39 extends angularly downward and communicates at its lower end with the top end of a discharge tube 40 screwed into the body and extending downwardly axially of the spout 38. The lower end of the tube 40 is even with or slightly below the bottom of the spout, so that the syrup is discharged from the tube at the center of the spout into a glass held thereunder.

Preferably, a disk 41 is secured within the top end of the spout 38 and has an annular groove 42 in its upper surface into which the carbonated water from the discharge duct 37 discharges, as shown in Fig. 6. An annular gasket 43 is inserted between the upper end of the spout and the faucet body 12 to form a leak-proof joint. As shown in Figs. 6 and 7, the disk 41 is provided with a plurality of circumferentially spaced downwardly directed and outwardly angled discharge ports 44 for discharging carbonated water from the annular groove 42 downwardly along the inner surface of the spout.

Thus, the annular groove 42 forms with the faucet body 12 an annular tube of enlarged cross sectional area for reducing the velocity and pressure of the carbonated water discharging from

the duct 37, and the combined area of the discharge ports 44 is several times that of the cross sectional area of the groove 42 so that a further reduction in velocity and pressure is effected causing the carbonated water to be discharged smoothly onto the inner surface of the spout without any material loss of carbon dioxide, in a condition sometimes called "soft soda." When a glass is held under the spout 38, the syrup and carbonated water may be discharged simultaneously into the glass for being mixed therein and the mixed drink contains a high proportion of carbon dioxide which is desirable.

The supply of syrup entering the syrup inlet passageway 29 from the supply tube 18 is regulated at the source of syrup supply so that the amount of syrup discharged from the tube 40 is in proper proportion to the amount of carbonated water being discharged simultaneously. However, means is provided in the syrup inlet passageway 29 for adjusting or regulating the syrup supply. This regulating means may be a screw 45 which is screwed into the body with its shank 46 intersecting the inlet passageway 29. As shown in Fig. 9, the shank 46 has a port 47 normally at least partly in register with the passageway 29, and by slightly turning the screw 45, this port may be adjusted to vary the amount of syrup flowing through the passageway 29.

The valves 32 and 32' are normally held closed by compression springs 48 engaging the front ends of the valves. As shown in Figs. 4 and 9, these springs are preferably located in counterbores in the front ends of the valves 32 and 32', and are held under compression by a cap plate 49 which is removably attached to the front of the body 12 by screws 50. The means for selectively opening the valves 32 and 32' against the pressure of the springs 48 consists of actuating pins 51 and 51' longitudinally slidably mounted in the body behind the flanges 34 and 34', respectively. As shown in Fig. 4, the pins are preferably hollow to reduce weight, and two pins are provided for each valve, one above and one below the center line, and preferably at the outside of the valve. The handle for selectively operating the valves 32 and 32' is indicated at 52, and has a yoke 53 which is pivotally mounted on opposite sides of the body 12. Preferably, the yoke is attached at each side of the body to cylindrical blocks 54 which are swiveled in the body, and as shown in Figs. 8 and 11, each swiveled block is provided with a notched-out cam surface 55 for engaging the rear ends of the pins 51 or 51' located on the corresponding side of the body.

As indicated in Fig. 8, when the handle 52 is pushed rearwardly, the lower edge of the cam surface 55 pushes the lower pin 51' forwardly to open the syrup valve 32' to the position indicated in Fig. 9. Obviously, the lower pin 51 engaging the flange 34 on valve 32 will at the same time open the carbonated water valve 32. Now if the handle 52 is pulled forwardly to the position of Fig. 10, the upper pins 51 and 51' will engage the flanges 34 and 34' and open both valves 32 and 32'. Thus, a mixed drink of flavoring syrup and carbonated water will be dispensed from the spout when the handle is moved to either of the dotted positions shown in Fig. 1.

Now if it is desired to dispense only carbonated water when the handle is pushed rearwardly, the lower pin 51' engaging the flange 34' is removed, and thus with the handle 52 in the position of Fig. 8, the valve 32' will not be opened, but the

valve 32 will be. If it should be desired to dispense only syrup when the handle is pushed rearwardly, the lower pin 51 which engages the flange 34 is removed, and the lower pin on the other side engaging the flange 34' is inserted, so that in the handle position of Fig. 8, the valve 32' is opened but the valve 32 is not. Obviously, by removing one or the other of the upper pins 51 or 51', syrup only or carbonated water only may be dispensed when the handle is pulled forwardly, and both syrup and carbonated water may then be dispensed simultaneously when the handle is pushed rearwardly.

The cap plate 49 is easily removed at any time by unscrewing the three screws 50, whereupon the valves 32 and 32' may be removed and the entire through passageways 28, 30, 33 and 29, 30', 33' may be thoroughly cleaned by means of a suitable brush. At the same time, the valve seats 31 and 31' may also be cleaned, as well as the seat inserts 36 on the ends of the valves. The passageways in the valve body are substantially self-cleaning, however, because the fluid makes only one right-angled bend within the body, and that occurs adjacent the valve seats 31 and 31' when the valves are moved axially away from the seats, allowing plenty of space for the liquids to flow from the inlet passageways 28 and 29 into the discharge ducts 37 and 39. Moreover, the discharge ducts are easily accessible for cleaning by merely unscrewing the spout 38 and discharge tube 40.

In order selectively to discharge carbonated water under high pressure from the spout, for making ice cream sodas and the like, a third valve 57 is slidably mounted above the other valves, preferably on the vertical center line of the body, as shown in Figs. 3 and 6. The valve 57 is slidably inserted from the front end of the body in a bore 58 having a valve seat 59 at its rear end, and an inlet passageway 60 of reduced area communicates with the center of the valve seat 59 which is located slightly behind the valve seats 31 and 31'.

The inlet passageway 60 extends longitudinally rearward but terminates short of the rear end of the body, and the rear end of the passageway 60 is connected by means of a downwardly and outwardly angled passageway 61 with the rear end of the inlet passageway 28, as shown in Figs. 3, 4, 5 and 6. Thus, the carbonated water supply duct 17 supplies carbonated water to both the inlet passageways 28 and 60 in the faucet body 12. A vertical discharge duct 62 of small diameter extends downwardly from the bore 58 in front of the valve seat 59 and communicates at its lower end with a discharge tube 63 which is screwed into the body and which passes through the disk 41 and terminates at the bottom of the spout.

A push lever handle 64 which may be a sheet metal stamping is preferably mounted on the cap plate 49 for operating the high pressure valve 57, and is preferably arranged so that it can conveniently be operated by pushing against its lower end with the palm of the hand when the fingers are in position to grasp the handle 52. Preferably, the lever 64 is fulcrumed on its underside at 65 on a lug 66 secured on the front of the cap plate, and the upper end of the lever is pivotally connected at 67 to the outer end of a reduced shaft portion 68 extending forwardly from the valve 57 through the cap plate.

Thus, pushing on the lower end of lever 64 will pull outwardly on the valve 57 and open the

valve. A compression spring 69 is interposed between the cap plate 49 and a shoulder on the valve 57 for urging the valve toward closed position, and an O-ring packing 70 is located in a groove around the inner end portion of the valve to seal off the bore 58 when the valve is open. Accordingly, the valve 57 may be selectively operated independently of valves 32 and 32' for discharging carbonated water under relatively high pressure entering from the same supply tube 17 which supplies carbonated water to the inlet passageway 28.

When the cap plate 49 is removed, the valve 57 and spring 69 will be removed with the cap, so that the bore 58, valve seat 59 and inlet passageway 60 are entirely open for being cleaned with a suitable brush at the same time as the other valve bores and inlet passageways are cleaned. Also, the discharge passageway 62 is easily accessible for cleaning when the spout 38 is unscrewed, merely by unscrewing the tube 63.

In addition to the advantages of being economically constructed out of stainless steel bar stock without requiring castings, and the ease of thoroughly cleaning the valve seats and passageways without disconnecting the faucet from the faucet arm, the novel faucet of the present invention has the advantage of giving an unusually large number of selections of beverage combinations, to suit a large variety of conditions, merely by omitting and rearranging certain of the pins 51 and 51'. For example, with two supply lines in the faucet arm, one supplying syrup and the other carbonated water (soda), the faucet can be arranged to dispense syrup, a mixed carbonated drink, and soda in accordance with the following table:

Top Handle Forward	Top Handle Rearward	Front Handle
1 Mixed Drink.....	Mixed Drink.....	High Pressure Soda.
2 .....do.....	Soft Soda.....	Do.
3 Soft Soda.....	Mixed Drink.....	Do.
4 .....do.....	Soft Soda.....	Do.
5 .....do.....	Syrup.....	Do.
6 Syrup.....	Soft Soda.....	Do.

Obviously, if tap water is supplied through one supply tube instead of the syrup, or instead of the soda, other combinations will result.

Moreover, if a third supply line is led in through the faucet arm, it can be connected directly to inlet passageway 60 and angular passageway 61 eliminated. This third supply line can supply tap water or fruit juice concentrate to obtain numerous other combinations of plain water, soda, mixed carbonated beverages, and fruit juice, as desired.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiment of the improved construction illustrated and described herein is by way of example, and the scope of the present invention is not limited to the exact details of construction.

Having now described the invention, the construction, the operation and use of a preferred embodiment thereof, and the advantageous new and useful results obtained thereby; the new and useful constructions, and reasonable mechanical

equivalents thereof obvious to those skilled in the art, are set forth in the appended claims.

I claim:

1. A beverage dispenser faucet including a body having front and rear ends and syrup and carbonated water straight passageways extending longitudinally therethrough from one end to the other, a valve seat in each passageway, valves slidably insertable into said passageways from the front ends thereof for seating on said seats to close the passageways, said body having discharge ducts communicating one with each said passageway in front of the valve seat therein, spring means in front of said valves, a cap removably attached to the front of said valve body for compressing said springs, a flange on each valve, release pins slidably mounted in said body engaging the rear side of said flanges, and a handle pivoted on said body and having cam surfaces engaging said release pins selectively for opening the valves against the pressure of said springs.

2. A beverage dispenser faucet including a body having front and rear ends and syrup and carbonated water straight passageways extending longitudinally therethrough from one end to the other, a valve seat in each passageway, valves slidably insertable into said passageways from the front ends thereof for seating on said seats to close the passageways, said body having discharge ducts communicating one with each said passageway in front of the valve seat therein, spring means in front of said valves, a cap removably attached to the front of said valve body for compressing said springs, a flange on one of said valves, a release pin slidably mounted in said body engaging the rear side of said flange, a handle pivoted on the side of said body and having a cam surface selectively actuating said pin for opening said one valve, another of said valves having a shaft projecting forwardly through said cap, and a handle lever pivoted to said projecting shaft for lifting said other valve off its seat.

3. In combination, a beverage dispenser faucet including a body having front and rear ends and syrup and carbonated water straight passageways extending longitudinally therethrough from one end to the other, said passageways terminating in a flat surface at the rear end of the body, a faucet arm shank having a front flat surface and syrup and carbonated water supply ducts terminating in said surface in register with the corresponding passageways in the body, a nut on the shank screwed on the rear end of the body for drawing said shank against the body, a valve seat in each passageway, valves extending slidably into said passageways from the front end thereof for seating on said seats to close the passageways, said body having discharge ducts communicating one with each said passageway in front of the valve seat therein, spring means in said passageways in front of said valves, a cap removably attached to the front of said valve body for compressing said springs, a flange on each valve, release pins slidably mounted in said body engaging the rear side of said flanges, and a handle pivoted on said body and having cam surfaces engaging said release pins selectively for opening the valves against the pressure of said springs.

4. In combination, a beverage dispenser faucet including a body having front and rear ends and syrup and carbonated water straight passageways extending longitudinally therethrough from one end to the other, said passageways termini-

nating in a flat surface at the rear end of the body, a faucet arm shank having a front flat surface and syrup and carbonated water supply ducts terminating in said surface in register with the corresponding passageways in the body, a nut on the shank screwed on the rear end of the body for drawing said shank against the body, a valve seat in each passageway, valves extending into said passageways from the front end thereof for seating on said seats to close the passageways, said body having discharge ducts communicating one with each said passageway in front of the valve seat therein, spring means in said passageways in front of said valves, a cap removably attached to the front of said valve body for compressing said springs, a flange on one of said valves, a release pin slidably mounted in said body engaging the rear side of said flange, a handle pivoted on the side of said body and having a cam surface selectively actuating said pin for opening said one valve, another of said valves having a shaft projecting forwardly through said cap, and a handle lever pivoted to said projecting shaft for lifting said other valve off its seat.

5. A beverage dispenser faucet including a body having front and rear ends and syrup and carbonated water straight passageways extending longitudinally therethrough from one end to the other, a valve seat in each passageway, valves slidable into said passageways from the front ends thereof for seating on said seats, said body having discharge ducts communicating one with each passageway in front of the valve seat therein, spring means in said passageways in front of said valves, a cap removably attached to the front of said valve body for compressing said spring means to close the valves, and a handle pivoted on said valve body for selectively actuating said valves, said valves and springs being removable when said cap is removed for cleaning said straight through passageways.

6. A beverage dispenser faucet including a body having front and rear ends and syrup and carbonated water straight passageways extending longitudinally therethrough from one end to the other, said passageways terminating in a flat surface at the rear end of said body whereby to register with supply ducts terminating at the front end of a faucet arm, means for detachably connecting said body to said faucet arm, a valve seat in each passageway, valves slidable into said passageways from the front ends thereof for seating on said seats, said body having discharge ducts communicating one with each passageway in front of the valve seat therein, spring means in said passageways in front of said valves, a cap removably attached to the front of said valve body for compressing said spring means to close the valves, and a handle pivoted on said valve body for selectively actuating said valves, said valves and springs being removable when said cap is removed for cleaning said straight through passageways.

7. A beverage dispenser faucet including a body having front and rear ends and syrup and carbonated water straight passageways extending longitudinally therethrough from one end to the other, a valve seat in each passageway, valves slidable into said passageways from the front ends thereof for seating on said seats, said body having discharge ducts communicating one with each passageway in front of the valve seat therein, spring means in said passageways in front of said valves, a cap removably attached to the front

of said valve body for compressing said spring means to close the valves, a handle pivoted on said valve body for selectively actuating said valves, said body having a longitudinal second water passageway provided with a valve seat therein, a valve slidable into said second water passageway from the front end of said body for seating on the valve seat, a spring between the second water valve and said cap, a separate handle lever operatively connected to said second water valve and fulcrumed on said cap, and all of said valves and springs being removable when the cap is removed for cleaning said passageways and valve seats.

15. 8. A beverage dispenser faucet including a body having front and rear ends and syrup and carbonated water straight passageways extending longitudinally therethrough from one end to the other, said passageways terminating in a flat surface at the rear end of said body whereby to register with supply ducts terminating at the front end of a faucet arm, means for detachably connecting said body to said faucet arm, a valve seat in each passageway, valves slidable into said passageways from the front ends thereof for seating on said seats, said body having discharge ducts communicating one with each passageway in front of the valve seat therein, spring means in said passageways in front of said valves, a cap removably attached to the front of said valve body for compressing said spring means to close the valves, a handle pivoted on said valve body for selectively actuating said valves, said body having a longitudinal second water passageway provided with a valve seat therein, a valve slidable into said second water passageway from the front end of said body for seating on the valve seat, a spring between the second water valve and said cap, a separate handle lever operatively connected to said second water valve and fulcrumed on said cap, and all of said valves and springs being removable when the cap is removed for cleaning said passageways and valve seats.

9. A beverage dispenser faucet including a cylindrical body having front and rear ends and passageways extending longitudinally entirely through said body from one end to the other, a valve seat in each passageway, valves slidably inserted into said passageways from their front ends, a cap removably attached to the front end of said body, springs between said valves and said cap urging said valves against said seats, a handle selectively operatively connected to said valves, a substantially cylindrical spout detachably connected to one side of said body, and said body having discharge ducts communicating one with each said passageway in front of the valve seat therein, said ducts discharging separately through said spout.

60. 10. A beverage dispenser faucet including a cylindrical body having front and rear ends and at least three longitudinal passageways, a valve seat in each passageway, valves slidably inserted axially into said passageways from their front end, a cap removably attached to the front end of said body, springs between said valves and said cap urging said valves against said seats, a handle pivoted on the side of said body and selectively operatively connected to two of said valves, and 65 a second handle operatively mounted on said cap and connected through the cap to said third valve, all of said valves and springs being removable when the cap is removed for cleaning said passageways and valve seats.

75. 11. A beverage dispenser faucet including a

11

cylindrical body having front and rear ends and at least three longitudinal passageways, a valve seat in each passageway, valves slidably inserted axially into said passageways from their front end, a cap removably attached to the front end of said body, springs between said valves and said cap urging said valves against said seats, a handle pivoted on the side of said body and operatively connected to two of said valves, a second handle operatively mounted on said cap and connected through the cap to said third valve, all of said valves and springs being removable when the cap is removed for cleaning said passageways and valve seats, a spout detachably connected to one side of said body, and said body having dis-
